US0D1109621S

(12) **United States Design Patent** (10) Patent No.: **US D1,109,621 S**
(45) Date of Patent: ** Jan. 20, 2026

(54) **ANALYTICAL PLATFORM FOR
BIOLOGICAL MATERIAL TESTING**

2300/0627; B01L 2300/0816; B01L
2300/0832; B01L 2300/0861; B01L
2400/0487

See application file for complete search history.

(71) Applicant: **Cellares Corporation**, South San
Francisco, CA (US)

CLAIM

The ornamental design for an analytical platform for biological material testing, as shown and described.

DESCRIPTION

FIG. 1 is a front right upper perspective view of a first embodiment of an analytical platform for biological material testing;

FIG. 2 is a front left upper perspective view of a first embodiment thereof;

FIG. 3 is a front view of a first embodiment thereof;

FIG. 4 is a rear view of a first embodiment thereof;

FIG. 5 is a left side view of a first embodiment thereof;

FIG. 6 is a right side view of a first embodiment thereof;

FIG. 7 is a top view of a first embodiment thereof; and,

FIG. 8 is a bottom view of a first embodiment thereof.

The stippling represents color where a first stippling pattern represents a first color, and a second stippling pattern represents a second color.
